UNITED STATES PATENT OFFICE

2,470,648

COMBINED ADJUSTABLE CURTAIN AND
BLIND BRACKET

John J. Rohleder, Baltimore, Md.

Application August 21, 1947, Serial No. 769,935

1 Claim. (Cl. 248—263)

1

This invention relates generally to supporting devices for window shades and curtains and is directed particularly to a bracket wherein a single two-part unit is provided to which an end of a shade roller and of a curtain rod may be attached.

A principal object of the present invention is to provide a bracket in two parts wherein one of the parts is firmly secured to the face of a window or door frame and the second part is adjustably maintained in position by the securement of the first part to the supporting body.

Another object of the invention is to provide an adjustable curtain and blind bracket which is so designed that the coacting parts may be readily stamped or punched from sheet metal of suitable weight and wherein one of the parts is pressed to receive the other part to maintain the latter in adjusted position when the pressed part is secured.

The invention will be best understood from a consideration of the following detailed description taken in connection with the accompanying drawing forming a part of the specification, with the understanding, however, that the invention is not to be understood as limited to the exact details of construction shown and described since obvious modifications will occur to a person skilled in the art.

In the drawing:

Figure 1 is a view in elevation of a pair of brackets constructed in accordance with the present invention and mounted in cooperative relation for the support of a shade roller and curtain bars or rods.

Figure 2 is a bottom edge view of the two brackets one thereof being in longitudinal section.

Figure 3 is a view in perspective of the adjustable plate element of a bracket designed for the support of an end of a shade roller and of a curtain rod.

Figure 4 is a view in end elevation of the fixed part or unit.

Referring now more particularly to the drawing the numeral 10 generally designates a bracket constructed in accordance with the present invention which in association with a similar bracket forms a pair for mounting upon the frame of a window or door, the same being shown in broken lines and designated 11.

Such bracket 10 comprises a fixed body plate 12 of generally rectangular form or contour, marginal edge portions of side strips of which are offset as indicated at 13 in a suitable manner as, for example, by performing a pressing operation upon

2

the central part of the plate, which central part is designated 14.

5 The marginal offset portions 13 of the plate are provided with suitable apertures 15 for the reception of holding or securing elements 16 such as screws or the like.

The central outpressed or outstanding portion 14 of the plate 12 is provided in one end edge with the recess 17 and spaced inwardly from this recess 10 is a cut-out or rectangular opening 18.

At the opposite end of the plate 12 from the recess 17 an integral portion of the plate is bent to extend at right angles from the top or outer face thereof to provide the curtain rod supporting 15 prong 19, a portion of which is turned back upon itself to provide the spring leg 20.

20 The numeral 21 designates a curtain rod, shown in broken lines, of the type wherein an end is formed as a flat sleeve which is designed to receive 25 the prong 19. As will be readily seen when such sleeve is slipped over the free end of the prong, the resilient backturned portion 20 will frictionally engage the inner wall of the sleeve so as to hold it firmly in position.

25 Associated with the fixed element or plate 12 and forming a part of the entire bracket unit 10 is the adjustable plate 22. This plate is of a width substantially equal to or slightly less than the width of the space 23 between the side strips or 30 portions 13 of the fixed plate.

One end of the adjustable plate 22 has an integral right angularly extending portion forming a rod supporting arm or prong 24, with the outer end of which is integrally formed or joined the 35 backturned resilient extension 25.

At the opposite end of the plate 22 is formed the right angularly extending plate or apertured arm 26 which projects from the same side of the adjustable plate 22 as the prong 24 and is in 40 spaced parallel relation with the prong 24 as shown in Figures 1 to 3.

The adjustable plate 22 is designed to position in the space or recess 23 between the side portions 13 of the fixed plate 12 where it is securely held 45 against movement longitudinally of the plate 12 when the screws 16 are drawn up tight to secure the plate 12 to the supporting body 11.

As shown in Figures 1 and 2 the curtain rod supporting prong 24 extends through the opening 50 18 of the body plate and the inner end of the prong 24 is provided at each side with the guide shoulders 27 which bear against the opposite longitudinal edges of the opening 18 to facilitate movement of the plate 22 lengthwise of the space 55 23 without binding.

The roller bracket 26 is positioned adjacent to the recessed end of the body plate 12 and may, if necessary, be moved back into the recess 17. This plate 26 is provided with an aperture or opening 28 to receive one of the trunnions 29 of a shade roller 30 which is shown in broken lines in Figures 1 and 2. Since one of the two supporting trunnions 29 of a shade roller is usually squared to hold a winding spring, it will be readily understood that in a pair of the units 10 the opening 28 of one roller plate 26 may be similarly formed to hold the trunnion against turning.

When a pair of the bracket units 10 is mounted in operative position desired or necessary adjustment may be made for the support of the shade roller 30 and a curtain rod 21 by loosening slightly the securing elements 16 for the plates 12 whereupon the adjustable plates 22 may be moved apart or together as may be desired. After proper positioning of the plates 22 has been attained they are firmly secured in place by tightening the screws 16, such action bringing the portion 14 of the covering plate 12 firmly against the top or outer face of the underlying plate 22 thereby frictionally holding the latter against movement.

Where use has previously been made of the usual curtain and shade supporting brackets secured by screws or nails, the plate 12 functions to cover up the old nail and screw holes.

I claim:

In an adjustable curtain and blind-supporting bracket, the combination with a body plate provided with a longitudinally-extending out-pressed portion, a side strip arranged on each

5 side of said out-pressed portion, there being a plurality of spaced apertures arranged in said side strips for receiving fastening elements for securing said body plate to a supporting surface, said body plate being provided with an opening 10 therein intermediate its ends, a prong arranged at right angles with respect to said body plate and having one end secured thereto for supporting a curtain rod, of an adjustable plate interposed between said supporting surface and said body plate and frictionally engaged by the out-pressed portion of the latter, a transversely-extending prong having one end secured to said adjustable plate and projecting through the opening 15 in said body plate for supporting a curtain rod, a shoulder arranged on each side of said last-named prong for preventing binding of said prong in said opening, and a transversely-disposed apertured arm projecting from said adjustable plate for supporting an end of a shade roller.

JOHN J. ROHLEDER.
